CARTON MAKING MACHINE

Alex S. Gibb, Bradenton, Fla., assignor to Continental Can Company, Inc., New York, N.Y., a corporation of New York

Filed May 20, 1958, Ser. No. 736,600

18 Claims. (Cl. 93—51)

This invention relates to machines for use in the manufacture of cartons from cardboard, fiber board and the like, and is similar to the machine disclosed in the U.S. patent application of Alex S. Gibb, Serial No. 630,938, filed December 27, 1956, now U.S. Patent No. 2,896,518, granted July 28, 1959.

In both machines, the cartons are formed from pre-cut blanks, each having a rectangular body, side flaps joined along fold lines to the longitudinal edges of said body, end flaps joined along fold lines to the end edges of said body, and corner flaps joined along fold lines to the ends of said side flaps. The blanks are successively fed to a forming station and either upon their arrival at this station or preferably prior to such arrival, adhesive is applied to the end areas of the end flaps for use in securing these end flaps against the corner flaps. Upon arrival at the forming station, the body of each blank underlies a rectangular expandable and contractible plunger and overlies a fixed rectangular throat frame, the side flaps overlie side flap folders, and the corner flaps overlie corner flap folders. The corner flap folders are first operated to upwardly fold the corner flaps from the side flaps. The side flap folders are next operated to upwardly fold the side flaps against the sides of the plunger and to thereby swing the upwardly folded corner flaps inwardly to positions at the ends of the plunger. Then the plunger is operated to depress the partly completed carton into the throat frame, and this causes upward swinging of the adhesive-carrying end flaps against the corner flaps. While the carton is in this throat frame, the plunger is longitudinally expanded to tightly press the end and corner flaps together for good union between them, and the plunger is then contracted and raised, leaving the carton in the throat frame to be pushed downwardly by the next formed carton and eventually conveyed from the machine. The dwell of the carton before conveyance from the machine allows time for the adhesive to set.

The machine of the above identified application was rapid and efficient but was restricted to the manufacture of cartons of one length, one width and one depth. This necessarily restricted the field of use of the machine. The present invention, however, has aimed to provide a new and improved construction permitting adjustment of the machine for the manufacture of cartons of various sizes and thus expanding the field of use of the machine.

In carrying out the above end, a further object has been to construct the throat frame from independent side and end members inwardly and outwardly shiftable to vary the size of said throat frame, and to mount the corner flap folders on said end members for shifting bodily therewith. Thus, when the side and end members are shifted to position them for a desired carton size, the corner flap folders and side flap folders are at the same time properly positioned without further adjustment.

The production of relatively deep cartons, requires that the plunger descend a greater distance than for rela-

2

tively shallow cartons; and a further object has been to provide a novel construction for effecting plunger descent to any required extent and for then stopping the descent, the stop means being quickly and easily adjustable as required.

The production of cartons of different sizes requires that the size of the plunger be readily changeable; and another object has been to make novel and advantageous provision for fulfilling this requirement.

5 A still further object has been to provide novel means for holding the inturned corner flaps against the ends of the plunger prior to upward folding of the end flaps, said means, however, being movable out of the paths of said end flaps as the latter are folded against inturned corner flaps.

With the above and other objects in view that will hereinafter appear, the nature of the invention will be more clearly understood by reference to the following detailed description, the appended claims and the several 15 views illustrated in the accompanying drawings.

In the drawings:

Figure 1 is a perspective view diagrammatically showing a magazine for the blanks, one blank fed from said magazine to a glue-applying station, and another blank 20 advanced to the carton-forming station.

Figure 2 is a diagram showing the corner flaps of the blank folded upwardly from the side flaps.

Figure 3 is a diagram showing the side flaps of the blank folded upwardly and the corner flaps consequently 30 swung inwardly.

Figure 4 is a diagram showing the partly completed carton of Figure 3 entering the throat frame and the end flaps consequently moving upwardly and inwardly for contact with the corner flaps.

35 Figure 5 is a perspective view of one of the completed cartons.

Figure 6 is an end view showing the construction at the carton-forming station. See the arrow 6 of Figure 8.

Figure 7 is an enlarged horizontal sectional view on 40 line 7—7 of Figures 6 and 8, partly broken away.

Figure 8 is a view partly in vertical section substantially on line 8—8 of Figure 7, and partly in elevation as indicated by the arrow 8 of Figure 6.

45 Figure 9 is an enlarged vertical longitudinal section through the upper part of the machine, as indicated by line 9—9 of Figure 6, but showing the plunger in a lower position.

Figure 10 is a similarly enlarged vertical longitudinal section through the lower portion of the machine on line 50 10—10 of Figures 6 and 7.

Figure 11 is a transverse vertical section on line 11—11 of Figures 7 and 10.

Figure 12 is a horizontal section on line 12—12 of 55 Figure 9.

Figure 13 is a vertical longitudinal section on line 13—13 of Figure 12.

Figure 14 is a vertical transverse section on line 14—14 of Figure 12.

60 The features of novelty shown in detail in the drawing are all embodied in the end of the machine positionally identified as "Carton-Forming station" in Figure 1. However, as the carton blanks B are to be mechanically fed from a suitable blank magazine to a glue-

65 applying station and each glued blank is to be then advanced to the forming station, the blank magazine and glue-applying stations have also been diagrammatically shown in Figure 1. In this same view a blank feeding means M is diagrammatically illustrated as operable by a pneumatic cylinder-and-piston assembly A. The feeding means M has been illustrated as having feed dogs F for feeding the blanks B one at a time to the glue-apply-

70

ing station, and a forwarding dog F¹ for advancing each glued blank to the carton forming station.

At the glue-applying station, spray nozzles N have been indicated for applying glue to the required areas of each blank B, but applicator rollers or any other preferred glue-applying means could, of course, be employed.

As the machine can be more easily understood after a general prologue explaining the form of blank to be used and briefly referring to principal machine elements without regard to specific structure, this procedure will be followed.

Prologue

Each blank B comprises a rectangular body B¹, two side flaps B² joined along fold lines to the longitudinal edges of said body B¹, two end flaps B³ joined along fold lines to the end edges of said body B¹, and four corner flaps B⁴ joined along fold lines to the ends of the side flaps B², respectively.

The required glue G is applied to the end areas of the end flaps B³ at the glue-applying station and the glued blank is then advanced to the forming station. At this station, the corner flaps B⁴ overlie folders 29 and the side flaps B² overlie folders 21. The corner flaps B⁴ are first folded upwardly to vertical positions as shown in Figure 2, by means of the corner flap folders 20. Then by means of the side flap folders 21, the side flaps B² are upwardly folded as shown in Figure 3. This movement inwardly swings the corner flaps B⁴ to positions at the ends of the body B¹, in readiness for upward folding of the end flaps B³. Prior to this latter operation, the folders 20 return to normal positions, but outward springing of the corner flaps B⁴ is then prevented by flap holding bars 22 shown in Figure 3. After partial folding of the blank as so far described, it is depressed by a plunger 23 into a rectangular throat frame 24 as shown in Figure 4, to thereby cause upward folding of the pre-glued end flaps B³ against the corner flaps B⁴. As soon as the end flaps B³ have started upwardly, the bars 22 are moved to out-of-the-way positions and the continued depression of the plunger 23 completes the upward folding of the end flaps B³ against the corner flaps B⁴. Then, the plunger 23 expands longitudinally to press the end and corner flaps tightly together to cause the glue to firmly bond them to each other. The plunger 23 then contracts and ascends to its normally raised position and the next glued blank is advanced between said plunger 23 and the throat frame 24. As the folding of this next blank is completed by depression into the throat frame 24, it downwardly moves the previously shaped carton and so on. The completed cartons C (Figure 5) successively leave the throat frame 24 and are conveyed away from the machine. In the meantime, the dwell of each carton C in the throat frame 24 has been sufficient to allow setting of the glue which secures the flaps B³ and B⁴ together.

Strictly speaking, the plunger 23, throat frame 24 and flap holding bars 22 would appear in all of Figures 1 to 4, but the disclosure has been simplified by showing these elements only in the views depicting their functions.

General frame structure

The frame structure of the machine is shown principally in Figures 6 to 11. Two longitudinal side bars 25 are supported by legs 26; and two transverse arched frames 27 have their lower ends secured upon said side bars 25. The upper ends of the arched frames 27 are rigidly connected by a longitudinal horizontal plate 28 (Figures 8 and 9).

Somewhat below the side bars 25, a horizontal rectangular frame 29 is secured to the legs 26. Upon this frame 29, a horizontal plate 30 is secured and this plate is formed with a rectangular opening 31. Each edge wall of this opening has a central notch 32. The plate 30 supports the throat frame 24 and the space surround-

ed by this throat frame communicates with the plate opening 31.

Throat frame

The throat frame 24 is shown in Figures 6 to 11 and comprises two side members 33 and two end members 34 each of which has a base 35 slidably inset in the top of the plate 30, a wall 36 rising from the inner edge of the base 35, and two end webs 37. Screw-and-slot connections 38 secure all of the bases 35 to the plate 30 and, when loosened, permit inward or outward shifting of the side and end members 33 and 34 according to the size of the cartons to be produced. Screws 39 are provided for shifting the side and end members 33 and 34 when the connections 38 are loosened. Each of these side and end members 33 and 34 is provided with a central downwardly projecting flap holding plate 40 which extends through the plate opening 31 and is flush with the inner side of the wall 36. Each plate 40 has a reinforcing rib 41 and the four ribs are received respectively in the four notches 32 in the side and edge walls of the opening 31.

The element 24a in Figures 7, 10 and 11 is simply a stripper to prevent possible ascent of a completed carton with the plunger 23.

Corner flap folders

The corner flap folders 20 are shown in Figures 6 to 11 and they are pivotally mounted on brackets 42 secured to the end webs 37 of the two throat frame end members 34. Pneumatic cylinder and piston assemblies 43 are also pivotally mounted on the end webs 37 of the end members 34 and are connected with the corner flap folders 20 for operating them. Inward or outward shifting of the end members 34, according to the length of the cartons to be produced, also shifts the corner flaps 20 and their operating means to the required new positions without requiring independent adjustment.

Side flap folders

The side flap folders 21 are shown in Figures 6 to 11 and they are pivotally mounted in bearings 44 secured to the walls 36 of the two throat frame side members 33. Pneumatic cylinder and piston assemblies 45 are mounted on the bases 35 of the side members 33 and are connected with the side flap folders 21 for operating them. Inward or outward shifting of the side members, according to the width of the cartons to be produced, also shifts the side flap folders and their operating means to the required new positions without requiring independent adjustments.

Plunger construction

The plunger 23 while shown on a small scale in Figures 6 and 8, is illustrated in detail in Figures 9 and 12 to 14. This plunger has a bottom plate 46, two side walls 47 detachably secured at 48 (Figure 14) to said bottom plate 46, and two projectable and retractable end walls 49. These end walls 49 have guide wings 50 slidably engaged with guides 51 on the side walls 47. These side walls are tied together at their upper edges by transverse tie bars 52 which are detachably secured at 53 thereto. By removing the side walls 47 and substituting thicker walls, to project laterally beyond the bottom plate 46, the width of the plunger 23 may be increased for the production of wider cartons, the side plates 47 herein shown being intended for use when cartons of minimum width are to be produced.

Provision is also made for varying the length of the plunger 23 for the production of cartons of a different length. Two aligned guides 54 are secured upon the bottom plate 46 near its ends; and two aligned horizontal stop bars 55 are slidably and non-rotatably mounted in said guides 54. The outer ends of the bars 55 have T-heads 56 to abut the end walls 49 and limit the in-

ward movement of these end walls. The inner ends of the bars 55 are connected by a turnbuckle 57 which may be held against longitudinal shifting in any preferred way, for example, by the forked plate 58 shown in Figure 12. By rotating the turnbuckle 57 in the required direction the stop bars 55 may be adjusted to effect lengthening or shortening of the plunger 23 according to the length of the cartons to be produced.

It will be recalled that after the folded carton blank has been completely depressed into the throat frame 24 by the plunger 23, this plunger is to be longitudinally extended to press the corner flaps B⁴ tightly against the end flaps B³. This is accomplished by outwardly projecting the plunger end walls 49; and for this purpose pneumatic cylinder and piston assemblies 59 are provided. The cylinders of these assemblies are secured upon the bottom plate 46 and the piston rods are secured to the end walls 49. Springs are preferably provided to retract the end walls 49 to allow ascent of the lowered plunger; and one of these springs is shown at 60 in Figure 13. When these springs are permitted to act, upon exhaust of air from the cylinders of the assemblies 59, the inward movement of the end walls 49 is limited by the positions to which the stop bars 55 have been adjusted.

The height of the plunger 23 is determined according to maximum depth of the cartons to be produced. However, for relatively shallow cartons, the plunger is not depressed as far as for deeper cartons. This is taken care of as explained below.

Plunger operating and stroke varying means

These means are illustrated primarily in Figure 9 but also appear in Figures 6 and 8 on a small scale. An arched yoke 61 has parallel vertical rods 62 extending slidably through openings 63 in the plate 28 which is mounted on the arched frames 27. The yoke 61 also has a crown bar 64 above the plate 28. The lower ends of the rods 62 are secured to the bottom plate 46 of the plunger 23 by means of brackets 65 which straddle the guides 54.

Pneumatic cylinder and piston assemblies 66 have their cylinders 67 secured to and projecting downwardly from the plate 28, in inwardly spaced parallel relation with the rods 62. The piston rods 68 of the assemblies 66 have upwardly projecting portions secured to the yoke crown bar 64 and downwardly projecting portions secured to the guides 54 of the plunger 23. Thus, the assemblies 66 are operable to depress and raise the plunger 23 as required.

As the ascent of the plunger 23 is always the same, regardless of the depth of the cartons being produced, fixed stops 69 may be provided on the lower ends of the piston rods 68 to strike the lower ends of the cylinders 67 and limit said ascent. However, as the plunger should descend a relatively short distance for shallow cartons and a greater distance for deeper cartons, the means for limiting the plunger descent is adjustable as explained below.

Two externally threaded tubular guides 70, for the piston rods 68 are secured at 71 upon the plate 28. Two stop sleeves 72 are threaded upon the guides 70; and two stops 73 are secured to the yoke 61 or to the rods 68 to strike the upper ends of said stop sleeves 72, to limit descent of the plunger 23. Thus, by rotating the stop sleeves 72 in one direction or the other and thus vertically adjusting them, plunger descent may be varied as required.

The two stop sleeves 72 are so connected that they can be adjusted only in unison. As an adequate connecting means, a spur gear 74 is mounted on the plate 28 between the stop sleeves 72 and these sleeves are provided with elongated gear teeth 75 meshing with the teeth of said gear 74. By turning this gear 74 in one direction or the other the stop sleeves 72 may be posi-

tionally adjusted as required. Friction may be relied upon to hold the gear 74 against accidental turning, or positive locking means may be employed.

Corner flap holders

The mounting and operating means for the corner flap holding bars 22 are shown in Figures 6, 8 and 9. One bracket 76 is secured to and projects downwardly from each end of the plate 28; a second bracket 77 is secured for vertical adjustment to said one bracket 76; a third bracket 78 is secured for horizontal adjustment to said second bracket 77; and the direction of adjustment of said third bracket 78 is longitudinally of the machine. The corner flap holding bars 22 are below the brackets just described but are secured respectively, to the lower ends of vertical arms 79, the upper ends of which are pivoted at 80 to the brackets 78, respectively, the pivots 80 being at right angles to the line of adjustment of said brackets 78 to allow swinging of said arms 79 toward and from the ends 49 of the plunger 23. Two hand levers 81 are fulcrumed at 82 to the two brackets 78, respectively, the fulcrums 82 being inwardly and downwardly spaced from the arm pivots 80 and being parallel therewith. A link 83 connects each lever 81 with the associated arm 79, said link being provided at 84 to said lever 81 and at 85 to said arm 79. Normally, each of the hand levers 81 occupies a lowered horizontal position as depicted at the left of Figure 9 and the corner flap holding bar 22 is then in cooperative relation with the plunger end 49. At this time, the link pivots 84 and 85 and the lever fulcrum 82 are on dead center and a stop arm 86 on the link 83 abuts the arm 79 to prevent further downward movement of the hand lever 81. Accidental upward movement of the lever 81 is prevented by the weight of its free end. Consequently, each corner flap holding bar 22 is stationarily held in spaced cooperative relation with the plunger end 49 to permit entrance of the corner flaps B⁴ between said bar 22 and plunger end 49 when said corner flaps B⁴ are moved from the positions of Figure 2 to those of Figure 3. However, as the plunger 23 initially descends and starts to cause upward folding of the end flaps B³ (Figure 4), the bars 22 remain stationary and slide off of the corner flaps B⁴ as the end flaps B³ move into contact with the corner flaps B⁴, the end flaps B³ clearing the bars 22. Under certain conditions a corner flap B⁴ will jam between one of the bars 22 and a plunger end when the corner flaps are swung from their positions of Figure 2 to their positions of Figure 3. When this occurs, the hand levers 81 are swung upwardly as depicted at the right of Figure 9, thereby causing the links 83 to outwardly swing the arms 79 and bars 22 to out-of-the-way positions.

Body blank guides

Two flanged track bars 87 (Figures 6, 7, 8, 10 and 11) are provided to support and guide each body blank B as it is fed to the forming station into position between the throat frame 24 and the normally raised plunger 23. These track bars 87 are adjustable inwardly and outwardly for blanks of one width or another, according to the size of the cartons to be produced. Both ends of these track bars 87 may be mounted and adjusted in substantially the same way but the mounting and adjusting means is shown for only one end of said track bars. These bars are provided with downwardly projecting blocks 88 slidably engaged with a fixed transverse track bar 89, the ends of which have supports 90 secured upon the main frame side bars 25. A transverse adjusting screw 91 is rotatably supported by the supports 90 and is threaded through the blocks 88 with a right hand thread for one block and a left hand thread for the other block. Thus, by simultaneously rotating the two adjusting screws, for the opposite ends of the track bars

87, in the same direction, said track bars may be adjusted inwardly or outwardly as required. The two screws are connected for simultaneous rotating, by a chain and sprockets. One of these sprockets is shown at 92 in Figures 6 and 7, and part of the chain is shown at 93 in Figure 7. Either screw may have a suitable hand wheel or crank for rotating it.

Machine activating switch

A switch 94 (Figures 6 and 8) is provided, to be closed by the blank B when said blank reaches its final position at the forming station, to activate the machine and produce a carton. This switch is mounted on a bracket bar 95 which is adjustable along brackets 96 secured to one of the throat frame end members 34. The switch 94 may thus be adjusted positionally according to the length of the blanks being handled by the machine.

Pneumatic system

The various cylinder and piston assemblies A (for the blank feeding means M of Figure 1), 43 (for the corner flap folders 20), 45 (for the side flap folders 21), 59 (for the plunger ends 49), and 66 (for the plunger 23), have suitable compressed air lines connected thereto and these lines have electrically operated air admission and exhaust valves. These valves are controlled by a timer driven by an electric motor which is started by the switch 94. Whenever this switch is closed by the blank B, the timer makes one revolution and during said revolution the various cylinder and piston assemblies function to cause operation of the feed means, flap folders and plunger in proper sequence.

As a good example of such a system is given in the patent application above referred to, the present case need not be encumbered by illustration and specific description.

Operation

As the foregoing explanation under the heading "Prologue" gives a good understanding, redundancy is avoided by not here recapitulating.

While the various features of the invention have been herein rather specifically described, it is to be understood that variations may well be made within the scope of the invention as claimed.

I claim:

1. In a machine for constructing a carton from a blank having a rectangular body, side and end flaps joined to said body, and corner flaps joined to said side flaps; a vertically fixed rectangular open throat frame to underlie said body, said throat frame having shiftably mounted upstanding side members adjustable inwardly and outwardly according to the width of said body, said throat frame also having shiftably mounted upstanding end members adjustable inwardly and outwardly according to the length of said body, means for securing said side and end members in fixed operational positions after positional adjustment thereof, corner flap folders hingedly mounted on the ends of said end members and shiftably bodily with these end members when positionally adjusting the same, said corner flap folders being operable to fold said corner flaps upwardly from said side flaps, side flap folders hingedly mounted on said side members and shiftably bodily with these side members when positionally adjusting the same, said side flap folders being operable to upwardly fold said side flaps and thus inwardly swing the upwardly folded corner flaps, and a plunger for then depressing the partly folded blank into said throat frame to cause upward folding of said end flaps against the inwardly swung corner flaps.

2. A structure as specified in claim 1; said plunger having means whereby its size may be varied according to the size of the blank body.

3. A structure as specified in claim 1, in which said side and end members are provided with downwardly projecting flap-engaging plates shiftable bodily with said side and end members when positionally adjusting these side and end members, said flap-engaging plates being flush with the inner sides of said side and end members.

4. A structure as specified in claim 1, in which said corner flap folders are provided with cylinder and piston assemblies for actuating them, said assemblies being mounted on the ends of said end members to shift bodily with these end members when positionally adjusting the same.

5. A structure as specified in claim 1, in which said side flap folders are provided with cylinder and piston assemblies for actuating them, said assemblies being mounted on said side members to shift bodily with these side members when positionally adjusting the same.

6. A structure as specified in claim 1, in which said corner flap folders are provided with cylinder and piston assemblies for actuating them, said assemblies being mounted on the ends of said end members to shift bodily with these end members when positionally adjusting the same, said side flap folders being also provided with cylinder and piston assemblies for actuating them, these assemblies being mounted on said side members to shift bodily with these side members when positionally adjusting the same.

7. A structure as specified in claim 1; in which a fixed horizontal supporting plate is provided for said side and end members said plate having an opening through which the carton is depressed by said plunger, said side, and end members each having a horizontal base resting on said supporting plate and a vertical wall integral with and rising from the inner edge of said base, each of said end members also having end webs integral with its base and plate, said corner flap folders and side flap folders having cylinder and piston assemblies for actuating the same, the cylinder and piston assemblies for said corner flap folders being mounted on the aforesaid end webs of said end members, the cylinder and piston assemblies for said side flap folders being mounted on the bases of said side members.

8. In a carton forming machine having a throat frame into which a partly folded carton blank is to be depressed to complete folding of said blank; a plunger to overlie the blank body, a fixed horizontal cylinder support mounted above said plunger, a yoke secured to and rising from said plunger, said yoke having a crown bar above said fixed cylinder support, two cylinder and piston assemblies for actuating said plunger, the cylinders of said assemblies being secured to and projecting downwardly from said cylinder support, said assemblies having piston rods projecting upwardly from said cylinders and secured at their upper ends to said crown bar of said yoke, two stops mounted on said cylinder support for vertical adjustment, said stops being disposed adjacent said piston rods respectively and being effective to limit descent of said plunger and yoke in accordance with the height of carton being formed, and connecting means between said two stops for insuring simultaneous adjustment thereof.

9. In a carton forming machine having a throat frame into which a partly folded carton blank is to be depressed to complete folding of said blank; a plunger to overlie the blank body, a fixed horizontal cylinder support mounted above said plunger, a yoke secured to and rising from said plunger, said yoke having a crown bar above said fixed cylinder support, two cylinder and piston assemblies for actuating said plunger, the cylinders of said assemblies being secured to and projecting downwardly from said cylinder support, said assemblies having piston rods projecting upwardly from said cylinders and secured at their upper ends to said crown bar of said yoke, two vertical tubular guides through which said piston rods extend slidably, the lower ends of said tubular guides being se-

cured to said cylinder support, the upper end of said tubular guides being downwardly spaced from the aforesaid crown bar of said yoke, two stop sleeves threaded for vertical adjustment on said two tubular guides respectively, said stop sleeves being effective to limit descent of said yoke and plunger in accordance with the height of carton being formed, and connecting means between said two stop sleeves for insuring simultaneous adjustment thereof.

10. A structure as specified in claim 9, in which said stop sleeves are provided with external vertically elongated gear teeth and in which a gear is mounted on the aforesaid cylinder support, the teeth of said gear being in mesh with the teeth of said stop sleeves, whereby rotation of said gear will rotate both of said stop sleeves to vertically adjust them in unison.

11. In a carton forming machine having a throat frame into which a partly folded carton blank is to be depressed to complete folding of said blank; a plunger to overlie the blank body, a fixed horizontal cylinder support mounted above said plunger, two cylinder and piston assemblies for actuating said plunger, said assemblies including cylinders secured to and projecting downwardly from said cylinder support and piston rods projecting both upwardly and downwardly from said cylinders, the lower ends of said piston rods being secured to said plunger, two stops mounted for vertical adjustment on said cylinder support and located adjacent the upwardly projecting portions of said piston rods respectively, stop means above the aforesaid two stops and movable bodily with said piston rods, said two stops being in the downward paths of said stop means to limit descent of said piston rods and plunger in accordance with the height of carton being formed, and connecting means between said two stops for insuring adjustment thereof in unison.

12. In a carton forming machine having a throat frame into which a partly folded carton blank is to be depressed to complete folding of said blank; a plunger to overlie the blank body, a fixed horizontal cylinder support mounted above said plunger, two cylinder and piston assemblies for actuating said plunger said assemblies including cylinders secured to and projecting downwardly from said cylinder support and piston rods projecting both upwardly and downwardly from said cylinders, the lower ends of said piston rods being secured to said plunger, two vertical tubular guides through which the upwardly extending portions of said piston rods extend slidably, the lower ends of said tubular guides being secured to said cylinder support, two stop sleeves threaded for vertical adjustment on said tubular guides respectively, stop means movable bodily with said piston rods, said two stop sleeves being in the downward paths of said stop means to limit descent of said piston rods and plunger in accordance with the height of carton being formed, and connecting means between said two stop sleeves for insuring adjustment thereof in unison.

13. A structure as specified in claim 12, in which said stop sleeves are provided with external vertically elongated gear teeth and in which a gear is mounted on the aforesaid cylinder support, the teeth of said gear being in mesh with the teeth of said stop sleeves, whereby rotation of said gear will rotate both of said stop sleeves to vertically adjust them in unison.

14. In a carton forming machine, a plunger to overlie the body of a carton blank, said plunger having side walls against which to upwardly fold side flaps of the blank, said plunger also having projectable and retractable end walls against which to upwardly fold end flaps of the blank, means for projecting and retracting said end walls while said plunger is within a folded blank, two adjustably mounted stops in the inward paths of said end walls respectively for limiting the retraction of these end walls, and connecting means between said stops for insuring simultaneous adjustment thereof.

15. In a carton forming machine, a plunger having

a bottom plate to overlie the body of a carton blank, said plunger having side walls secured to said bottom plate and against which to upwardly fold side flaps of the carton blank, said plunger also having projectable and retractable end walls against which to upwardly fold end flaps of the blank, means for projecting and retracting said end walls while said plunger is within a folded blank, two aligned stop bars slidably mounted on said bottom plate and having their outer ends disposed to limit the retraction of said end walls, and a turnbuckle connecting the inner ends of said stop bars for simultaneously adjusting them outwardly or inwardly according to the length of the blank body.

16. In a machine for forming a carton from a carton blank having a body, side and end flaps connected to said body, and corner flaps connected to said side flaps, said machine having a plunger against which to upwardly fold said side flaps after first upwardly folding said corner flaps, whereby said corner flaps will occupy positions at the ends of said plunger when said side flaps are upwardly folded and the blank will thus be in readiness for upward folding of said end flaps against said corner flaps, corner flap holding members spaced outwardly of said plunger ends to abut and temporarily hold said corner flaps at said plunger ends, means mounting said corner flap holding members for outward shifting, the mounting means for each of said corner flap holding members including an arm carrying the holding member, a fixed bracket to which the upper end of said arm is pivoted, a vertically swingable hand lever fulcrumed at one end to said bracket, a link pivoted to both said arm and said bracket for outwardly swinging said arm as said lever is upwardly moved and vice versa, and means for limiting the downward movement of said lever to a position in which the lever fulcrum and the link pivots are on or past dead center to then stationarily hold said arm and the flap holding member carried thereby.

17. In a carton forming machine having a throat frame into which a partially folded carton blank is to be depressed to complete folding of said blank; a plunger to overlie the body blank, a fixed horizontal cylinder support mounted above said plunger, a yoke secured to and rising from outer portions of said plunger, said yoke having a crown bar above said fixed cylinder support, two cylinder and piston assemblies for actuating said plunger, the cylinders of said assemblies being secured to and projecting downwardly from said cylinder support, said cylinders having piston rods extending upwardly and downwardly from said cylinders, said piston rods having their upper ends secured to said crown bar and their lower ends secured to said plunger inwardly of the connections between said yoke and said plunger to provide for the stable supporting of said plunger.

18. In a carton forming machine having a throat frame into which a partially folded carton blank is to be depressed to complete folding of said blank; a plunger to overlie the body blank, a fixed horizontal cylinder support mounted above said plunger, a yoke secured to and rising from outer portions of said plunger, said yoke having a crown bar above said fixed cylinder support, two cylinder and piston assemblies for actuating said plunger, the cylinders of said assemblies being secured to and projecting downwardly from said cylinder support, said cylinders having piston rods extending upwardly and downwardly from said cylinders, said piston rods having their upper ends secured to said crown bar and their lower ends secured to said plunger inwardly of the connections between said yoke and said plunger to provide for the stable supporting of said plunger, and stop means mounted for vertical adjustment on said cylinder support and effective to limit descent of said yoke and said plunger in accordance with the height of carton being formed.
